Charles Lee and Clarence Johnson,
Eau Claire, Wis.

Application May 19, 1947, Serial No. 139,138

Term of patent 7 years

(Cl. D17—12)

To all whom it may concern:

Be it known, that we, Charles Lee and Clarence Johnson, citizens of the United States, residing at Eau Claire, county of Eau Claire, and State of Wisconsin, have invented a new, original, and ornamental Design for a Coat Hanger Supporting Hook for Automobiles, of which the following is a specification, reference being had to the accompanying drawing, forming part thereof, and in which

Fig. 1 is a side elevational view showing a coat hanger supporting hook for automobiles, showing our new design;

Fig. 2 is a top view of Fig. 1;

Fig. 3 is a bottom view of Fig. 1;

Fig. 4 is an end view of the device looking at it from the left as shown in Fig. 1; and

Fig. 5 is a view showing the opposite end of the device.

We claim:

The ornamental design for a coat hanger supporting hook for automobiles, substantially as shown.

CHARLES LEE,
CLARENCE JOHNSON.
